UNITED STATES PATENT OFFICE.

JOHN GLEN, OF BROOKLYN, NEW YORK.

DESIGN FOR A PRINTED FABRIC.

SPECIFICATION forming part of Design No. 13,146, dated August 8, 1882.

Application filed July 1, 1882. Term of patent 3½ years.

To all whom it may concern:

Be it known that I, JOHN GLEN, of Brooklyn, Kings county, in the State of New York, have invented a new and original Design for Printed Fabrics; and I do hereby declare that the following specification, taken in connection with the accompanying illustration, forming a part of the same, is a full, clear, and exact description thereof.

10 My design relates particularly to printed fabrics known as "calicoes," although it is equally applicable to silks, woolens, and other fabrics, either printed or woven.

15 It consists in the representation of sprays of flowers, as will hereinafter appear.

Referring to the illustration, A represents a stem, which bears leaves B and flowers C. Branching from the stem A is also a stem bearing buds b; but this latter stem and the buds

may be omitted, if desired. The stem, leaves, 20 and flowers constitute the spray, which is repeated upon the surface of the fabric to form the pattern.

The fabric may be produced in any preferred variety or combination of colors for giving a 25 desirable effect to the design.

What I claim, and desire to secure by Letters Patent, is—

1. The design for printed and other fabrics, consisting of sprays of flowers, substantially 30 as set forth.

2. The design for printed and other fabrics, consisting of sprays of flowers bearing buds, substantially as described and shown.

JOHN GLEN.
